United States Patent Office

Des. 227,839
Patented July 24, 1973

227,839

DRESSER WITH CARVED DETAILS OR THE LIKE

Joseph E. Adkinson, 3807 Leland St.,
Chevy Chase, Md. 20015

Filed Feb. 4, 1972, Ser. No. 223,819

Term of patent 14 years

Int. Cl. D6—04

U.S. Cl. D6—154

FIG. 1

FIG. 2

FIG. 3

FIG. 1 is a view in front elevation of a dresser as shown in my design.

FIG. 2 is a view in side elevation of the dresser of FIG. 1.

FIG. 3 is a view in top plan of the dresser of FIG. 1.

The side of the dresser not shown is like the side shown, while the back is conventionally flat.

I claim:

The ornamental design for a dresser with carved details or the like, substantially as shown and described.
